[57] CLAIM

The ornamental design for a bottle, substantially as shown and described.

DESCRIPTION

FIG. 1 is a perspective view of a bottle showing our new design;

FIG. 2 is an elevational view thereof with the cap removed, the opposite side being substantially a mirror image thereof;

FIG. 3 is an elevational view looking from the right of FIG. 1;

FIG. 4 is a bottom plan view;

FIG. 5 is a top plan view;

FIG. 6 is a perspective view showing a modified form of our new design; and

FIG. 7 is an enlarged, fragmentary sectional view taken on the line 7—7 of FIG. 2.
